FASTENER

Daniel A. Brennan, deceased, late of Chicago, Ill.,
by Elmer L. Zwickel, executor, Chicago, Ill., as-
signor to Acco Products, Inc., Long Island City,
N. Y., a corporation of New York

Original application December 16, 1940, Serial No.
370,372. Divided and this application July 22,
1942, Serial No. 451,846

7 Claims. (Cl. 24—153)

This application is a division of applicant's co-pending application Serial No. 370,372, filed December 16, 1940.

The invention relates broadly to a paper fastener compressor of a type to be associated with a base having spaced prongs adapted to be extended through openings in a stack of papers and bent over the top face of said stack for binding them together; and more particularly to a compressor including resiliently flexible means for engaging and holding the prongs in bent over concealed position.

An object of the invention is to provide a resiliently flexible paper fastener compressor having novel means to cooperate with prongs of an associated base to hold them together in bent down position over the papers.

Another object is to provide a paper fastener compressor embodying resiliently flexible means manually depressible to effect disengagement of its prong engaging means from the prongs.

Another object is to provide a paper fastener compressor, of the type adapted to have yieldable gripping means engageable with prongs of an associated base, which is easy to assemble in place on a stack of papers, simple to operate, positive in operation, and inexpensive to manufacture.

The foregoing and such other objects of the invention as will appear hereinafter as the description proceeds, will be more readily understood from a perusal of the following specification, in which, reference is had to the accompanying drawing; wherein:

Fig. 1 is a plan view of an embodiment of the compressor showing it attached to prongs of an associated base element.

Fig. 2 is a longitudinal sectional view taken on line 2—2 of Fig. 1.

Fig. 3 is a fragmentary plan view of one of the two identical ends of another form of compressor, showing it associated with an underlying prong.

Fig. 4 is a transverse sectional view taken on line 4—4 of Fig. 3.

Referring to the form of fastener illustrated in Figs. 1 and 2, the fastener includes a base element 11 having spaced apart bendable prongs 12 at each end. The base element 11 is adapted to be placed against one face of a stack of loose sheets 13 with its prongs extending through aligned holes therein and bent down inwardly toward each other over and against the other face of said stack.

A compressor 15, formed of a strip of resiliently flexible sheet material such as, for example;

sheet steel, pressboard, plastic, or the like, is arranged over the bent down prong portions.

Displacement of the compressor 15 is avoided by providing suitable detents or lips 16 on the bottom face of the compressor, preferably along each longitudinal edge thereof, which extend but a short distance inwardly from each end. As shown, the lips 16 are arranged in pairs spaced apart a distance substantially equal to the width of the prongs and suitably deformed to have a snapping or yieldable gripping engagement with the side edges of the underlying prong portion adjacent their bends.

The compressor 15 preferably embodies means whereby the lips 16 may easily and quickly be disengaged from their gripping engagement with the underlying prongs for removal of the compressor. Such means preferably is provided adjacent each end thereof, and may include transverse ribs 17 struck downwardly in the compressor body one inwardly of and closely adjacent to the inner terminal of respective pairs of lips 16. The ribs 17 project below the bottom face of compressor 15 a distance slightly less than the depth of lips 16 so as to rest firmly upon the top surface of the underlying prong while said lips are in yieldable gripping engagement therewith.

The medial portion of the compressor strip preferably is depressed as at 18 also into the plane of the ribs 17. As best shown in Fig. 2, the centrally depressed portion 18 terminates a suitable distance short of each rib 17 so as to define an elevated degressive bridge portion 19 inwardly of each rib 17. If desired the depressed medial portion 18 of the compressor may be suitably reinforced against flexing by an offset preferably in the form of a central longitudinal rib 21.

When the compressor is mounted securely in place both end portions thereof assume positions substantial as illustrated in the left hand end of the fastener shown in Fig. 2. In order to easily and quickly remove the compressor, the degressive portion 19 at each end is depressed manually, as illustrated at the right hand side of Fig. 2, causing the extreme end portion of the compressor to flex upwardly angularly relative to the normal plane of the compressor. This upward flexing momentarily of the end portions of the compressor pulls the lips 16 out of engagement of the underlying prong and the compressor is freed for easy removal. The prongs may then be straightened and papers added to or removed from the stack.

It should be evident at this time that the in-

stant structure permits a more firm gripping action by the lips 16 than might ordinarily be practical with a one piece compressor inasmuch as positive means is provided integral with said compressor to effect separation of the parts.

The compressor illustrated in Figs. 3 and 4 is functionally and generally like that previously described. In this arrangement, short longitudinally extending ribs 22 are provided on the bottom face of the compressor one inwardly of and co-extensive with each detent or lip 16. These ribs, like the transverse ribs 17 of the previously described device, rest against the top face of underlying prong portion 12 when the lips are in yieldable gripping engagement with said prong. The portion of the compressor at each end between the ribs 22 may be provided with an elevated portion or projection 23 so as to facilitate manual depression of said portion to effect outward spreading of the lips 16 to release the underlying prong portion.

Although exemplary forms of the improved compressor have been shown in the accompanying drawing and described in detail in the foregoing specification, it should be understood that each device may embody a variety of modifications without departing from the spirit of the invention or the scope of appended claims.

What is claimed is:

1. A fastener compressor comprising an elongated resiliently flexible strip adapted to overlie prongs of an associated base element after said prongs are bent down against the top face of a file of papers, transverse ribs on the bottom face of said strip one inwardly of each end adapted to bear against the prongs when the strip is in position thereover, a pair of lips on each end of said strip extending between said ribs and the associated ends, said lips being adapted to embrace said bent down prongs to hold the strip in place thereover, and a depressible portion in said strip inwardly of each rib effective when depressed to urge the end portions of the strip upwardly to disengage the lips from said prongs.

2. A compressor for paper fasteners comprising an elongated strip of sheet material adapted to overlie prongs of an associated base element after said prongs are bent down against the top face of a stack of papers to be bound, spaced longitudinal detents at each end of said compressor adapted to engage said prongs, a transverse rib adjacent each end of the compressor each projecting in the same direction as said detents, and

the center portion of said strip being offset downwardly into the plane of the ribs to define an elevated portion at each end inwardly of said ribs depressible to effect separation of the detents from the prongs.

3. A fastener compressor comprising a resiliently flexible strip having a pair of spaced lips extending inwardly a short distance from each end, transverse ribs in said strip one inwardly of each pair of lips, and an offset in said plate spaced from and disposed substantially in the same plane as said ribs, said ribs and offset defining parts inwardly of each rib manually engageable to deflect the end portions angularly to the plane of the strip.

4. In a paper fastener compressor, in combination, spaced elements at the ends of said compressor adapted to yieldingly embrace prongs of an associated base member, and resilient means in said compressor associated with but spaced from said elements effective when depressed to disengage said elements from the prongs.

5. A fastener compressor comprising a strip of thin sheet material adapted to be positioned over at least one bent down prong of an associated base element, spaced lips on at least one end of said strip adapted to embracingly engage said prong, a pair of spaced longitudinal ribs at said end of the strip projecting in the same direction as and one adjacent each lip, and a projection between said ribs extending in the opposite direction from said ribs, pressure on said projection effecting release of said lips from the prong.

6. A one-piece fastener compressor comprising a resiliently flexible strip having depending lips on its longitudinal edges extending inwardly longitudinally from each end adapted to cooperate with prongs of an associated base member, and a depressible portion in said strip between said lips at each end effective to spread the lips apart transversely.

7. In a paper fastener compressor, in combination, spaced elements integral with the ends of said compressor adapted to yieldingly embrace the prongs of an associated base member, and resilient means in said compressor spaced from but associated with said elements effective when depressed to disengage said elements from the prongs.
